Primary Examiner — John R Yeh(74) *Attorney, Agent, or Firm* — Steven E. Jedlinski; Jeffrey T. Placker; Holland & Knight LLP(57) **CLAIM**

The ornamental design for a pressure washer frame, as shown and described.

DESCRIPTION

FIG. 1 is a front-left perspective view of a pressure washer frame in an unfolded configuration;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front-left perspective view of the pressure washer frame of FIG. 1 in a folded configuration;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines are included for the purpose of illustrating portions of the pressure washer frame that form no part of the claimed design.

1 Claim, 14 Drawing Sheets(56)
